PROTECTING DEVICE FOR TELEPHONE
TRANSMITTERS

Maurice Rubel, Chicago, Ill.

Application January 11, 1935, Serial No. 1,392

2 Claims. (Cl. 179—185)

This invention relates to a protecting device for the transmitter of a telephone and the like, and more particularly to a device for feeding a long strip of paper before the mouth of the transmitter upon repeated manipulations.

A considerable number of caps and other protecting devices for the transmitter of a telephone have been devised to prevent the spread of disease through the use of public telephones; however, as far as I am aware, no device has been found acceptable or satisfactory. The difficulty of dispensing caps or short strips of paper and the accumulation of waste caps etc. after use have made such plans undesirable.

An object of my invention is to provide means whereby a fresh strip of paper can be fed with a modicum of effort into position bridging the transmitter mouth, and means for compactly storing the waste strip until a time when it may be conveniently disposed of. A further object is to provide means for preventing waste of the paper during the time that the telephone is being used. A still further object is to provide automatic means for feeding fresh paper areas each time the telephone is used. Other specific objects and advantages will appear as the specification proceeds.

The invention is illustrated, in a preferred embodiment, by the accompanying drawings, in which—

Figure 1 is a front view in elevation of a telephone transmitter equipped with a device embodying my invention; Fig. 2, a side view in elevation; Fig. 3, a sectional view, the section being taken as indicated at line 3 of Fig. 2; Fig. 4, an end view of the lower cylindrical casing, the cap being removed, the view being indicated by the line 4 of Fig. 3; Fig. 5, a view similar to Fig. 4 of the opposite end of the cylindrical casing, the view being taken at line 5 of Fig. 3; Fig. 6, a transverse sectional view of my device, the section being taken as indicated at line 6 of Fig. 2; and Fig. 7, a side view in elevation of a modified form of the invention in which paper is fed automatically upon movement of the receiver hook, the end cap of the lower cylindrical casing being removed.

In the illustration given, A designates the telephone stand equipped with a receiver hook A'; B, a receiver; and C, the transmitter. In view of the fact that such construction is well known, a detailed description is believed unnecessary.

My attachment mechanism comprises a rear metal wall 10 which is centrally perforated to receive the rear end of the mouthpiece 11; that

is, the mouthpiece 11 is first removed and then after being passed through the central apertured plate 10, is screwed within the drum casing 12. Secured to the rear side of plate 10 is an annular socket 13 adapted to receive the drum 12. 5 Screws 14 are passed through the socket member 13 and engage the drum casing 12 to secure the attachment rigidly to the drum casing. Soldered to the ends of plate 10 are the upper cylindrical casing 15 and the lower cylindrical casing 10 16. The casings are provided with caps 15^a and 16^a respectively. Casing 15 is provided with a slot 17 which runs to the extreme open end of the casing, and likewise casing 16 is provided with a slot 18 which runs to its extreme open 15 end. Thus, when the caps 15^a and 16^a are removed, the slots 17 and 18 permit the rolls of paper inside to be removed with a web of paper connecting the rolls. Connecting the casings 15 and 16 is a metal platen member 19 having 20 its sides turned inwardly to provide U-shaped guides 20 receiving the edges of the paper. The platen is provided with openings 21 in its central portion and adjacent the mouth 11 of the transmitter.

The upper cylindrical casing 15 receives a simple roll 22 containing paper 23. The roll or spool 22 is provided with sides 23. The paper from the upper spool 22 passes through the slot 17 over the platen 19 and is attached to a lower 30 spool 24, which is equipped at one end with an operating wing or thumb button 25. The lower spool 24 is preferably equipped with an inclined spring stop member 26 which is adapted to engage a fixed abutment 27, as shown more 35 clearly in Fig. 4, to prevent the spool from being turned in an unwinding direction.

It will be observed that the winding handle 25 is disposed on the same side of the telephone stand as the receiver B. Thus, when 40 the telephone is being used, the user of the telephone having the receiver grasped in his left hand, is unable to reach and manipulate the handle 25. This prevents the user from wantonly operating the mechanism to use up the paper 45 supply. In view of the fact that the paper roll may contain advertisements, there would doubtless be a tendency for the user of the telephone to wind up the bottom roll while telephoning, if this could be done conveniently.

If desired, additional means may be provided for preventing the user of the telephone from winding the bottom roll. As illustrated more clearly in Fig. 5, the inner end of the spool roll 50 may be equipped with a ratchet gear 28. A 55

pawl 29 is urged into engagement with the gear 28 by a spring-pressed pin 30. The pawl 29 is provided with a curved portion extending about the gear 28 and with a vertical stem extending through casing 16 and provided with a push button 31. With this construction, it is necessary for the operator to depress the button 31 with one hand in order to operate the winding piece 25 with the other.

10 If desired, the bottom of casing 16 may be provided with a highly efficacious disinfectant, and a continuous web might be looped about the spools 22 and 24.

In the modification illustrated in Fig. 7, the construction is substantially the same as that shown in the other figures, except that automatic mechanism is provided for operating the lower spool. A fixed bracket 32 is clamped to the telephone stand and supports the abutment 33 to which is pivoted the lever arm 34. The lever arm 34 is provided with a short arm 35 adapted to be engaged by the receiver hook A' when the receiver is placed thereon and allowed to fall. The downward movement of the receiver hook depresses the arm 35 and elevates the long arm 36 of lever 34. Pivots connected to the end of the arm 36 is a rack 37 which engages the gear sleeve 38. The rack teeth are held in engagement with gear sleeve 38 by a grooved roller 39 which engages the rear of rack 37. The shaft of the spool carrying the paper is provided with a curved or cam end 40, as shown more clearly in Fig. 7. The configuration of the end affords chambers between it and the gear sleeve 38 adapted to receive balls 41. The chambers are shaped, as in a free wheeling clutch, so that when the rack 37 moves upwardly, the balls 41 are forced toward the narrow end of the chambers and thus engage the shaft end 40 to rotate the shaft. On the downward stroke of the rack, the balls 41 are drawn toward the large end of the chamber, and the gear sleeve 38 overruns.

It will thus be observed that whenever the receiver B is placed on hook A', the weight of the receiver causes the hook to drop and the engagement of the hook A' with the short arm 35 elevates arm 36 and rack 37, thus effecting a rotary movement of the spool shaft 40 so as to draw a fresh paper area across the platen 19.

50 In the operation of the mechanism shown in Figs. 1 to 6 inclusive, the rolls 15 and 16 may be loaded by removing the caps 15^a and 16^a, attaching the end of the paper carried by spool 26 to spool 24, and placing each of the spools within its respective cylindrical casing. The paper connecting the two spools slips through the slots 17 and 18 of the respective casings, and the edges

of the paper are received within the guides 20 of platen 19. In inserting the lower spool 24 within the casing 16, the operator depresses button 31 so as to depress the pawl 29 until the ratchet 28 is in alignment therewith. The caps 15^a and 16^a may then be placed in position and the device is ready for operation. When a user reaches the telephone, he first depresses the button 31 and operates the handle 25 to draw a fresh area of paper across the platen. He then grasps receiver B and operates the telephone in the usual manner.

If desired, a block or pack of paper sheets might be substituted for the roll, the user tearing off the used sheet before telephoning.

15 Directions as to the use of the telephone may be placed upon the upper cylindrical casing 15, or upon any other suitable part of the attachment. If desired, the paper on the spools may be covered with advertisements which will discourage the user from writing or making notes upon the paper fastened over the platen.

20 While in the foregoing description, I have set forth a certain specific construction by way of illustration, it will be understood that the principles of my invention may be employed in widely differing forms of mechanism. The foregoing detailed description has been given for clearness of understanding only, and no unnecessary limitations should be understood therefrom, but the 25 appended claims should be construed as broadly as permissible, in view of the prior art.

I claim:

1. In combination with the transmitter of a telephone, a casing secured to said transmitter, a 35 paper roll supported in said casing, manually operated means for drawing paper from said roll in front of said transmitter, and latch means restraining operation of said first named means located remotely from said first named means, 40 whereby both hands of the operator are required to operate said first and second named means.

2. In combination with the transmitter of a telephone, a casing secured to said transmitter, a paper roll supported in said casing, a rotatable 45 member on which the paper is wound from said roll, said member having a portion at which said member is adapted to be rotated to draw the paper from said roll in front of said transmitter, a ratchet secured to rotate with the paper in its movement, and a latch cooperating with said ratchet and restraining movement of the latter to prevent feeding of the paper, said latch being located remotely from said portion, whereby both hands of the operator are required to operate 50 said portion and said latch.

55 MAURICE RUBEL.
